UNITED STATES PATENT OFFICE.

HERBERT E. WHITE, OF NILES, OHIO, ASSIGNOR TO INTERNATIONAL METAL LATH COMPANY, A CORPORATION OF NEW JERSEY.

SLITTED BLANK FOR EXPANDED METAL STRUCTURES.

SPECIFICATION forming part of Letters Patent No. 689,939, dated December 31, 1901.

Application filed August 11, 1900. Serial No. 26,573. (No model.)

To all whom it may concern:

Be it known that I, HERBERT E. WHITE, mechanical engineer, a resident of Niles, in the county of Trumbull and State of Ohio, have 5 invented certain new and useful Improvements in Slitted Blanks for Expanded Metal Structures, of which the following is a description, illustrated by the accompanying drawings.

10 The invention relates to slitted blanks for forming expanded metal structures having alternate ribs and slatted open-work sections, examples of which are to be seen in United States Letters Patent No. 651,643, granted to me June 12, 1900. In such expanded metal structures it is usual first to cut the series 15 of slits as required by means of suitable dies and thereafter to expand the slitted blanks in various manners. Much difficulty has 20 heretofore generally been encountered in the expanding of such sheets, and special processes, many of them slow and tedious, have been devised to accomplish the regular and even expansion of the sheets without tearing 25 the metal. The present invention is based on the discovery of a simple expedient by which the expansion of the metal in the proper manner may be assured and greatly facilitated.

30 I have discovered that in slitting the metal slight burs or rough edges are formed in the slits, and these seriously interfere with the expansion of the metal in any manner that requires the passage of the burred or roughened edges of the slit by each other in any direction except that in which the cutting-dies have originally acted upon them in the operation of making the slit. By causing the dies which form the slits to slightly twist and 35 incline the narrow slats or strips of metal between adjacent slits in the same direction in which they are to be subsequently opened in the expanding process I have discovered that I not only can greatly facilitate the usual expanding processes, but also the slitted blank 40 so formed is capable of being expanded in the regular and in the desired manner by merely applying the expanding force to its extreme edges.

The invention will be best understood by 50 an immediate description of the accompanying drawings, wherein—

Figure 1 shows a corner portion of a slitted blank embodying the present invention. Fig. 2 is a cross-section thereof on the plane 55 2 2 of Fig. 1 looking toward the left-hand. Fig. 3 is a section on the plane 3 3 looking toward the left hand. Fig. 4 is a partial section on the oblique plane 4 4 looking toward the left hand. Fig. 5 is a section at right angles to the ribs on the plane 5 5 of Fig. 1 and also showing in cross-section two cutting-dies in position to cut one of the slits. Fig. 6 is one form of the expanded structure that can be produced from my improved slitted 65 blank.

The ribs are marked r' r'' r''' , and the slats between the ribs are marked s' , s'' , and s''' . In cutting the slits between the ribs r' and r'' the edges of the slits are slightly displaced, so 70 as to twist or incline slightly the strips s' , as shown in Figs. 2 and 5. In Fig. 5 a pair of dies d are shown in section in position as they act upon the metal in the shearing operation. As a result of this twist or inclination 75 of the metal the rib r'' may be readily raised relatively to the rib r' or the rib r' may be depressed relatively to the rib r'' , which is another way of expressing the same relation; but if it is attempted to raise the rib r' relatively to the rib r'' the rough edges of the strips s' catch and interfere with the expansion. In the second slitted section the strips 80 s'' are twisted or inclined in the same direction as the strips s' , as viewed in Fig. 5 and 85 as will be plainly understood from a consideration of Figs. 3 and 5 together. Consequently the rib r''' may be raised relatively to the rib r'' , expanding the slats s'' , as shown in Fig. 6. Similarly the slats or strips s''' are 90 twisted or inclined in the same direction, as seen in section, at right angles to the ribs, Fig. 5. In a slitted sheet of this character, having all the slats initially twisted or inclined, as described, and gripped by the ribs 95 at its extreme edges and these ribs drawn apart, the entire sheet will expand without the aid of any other instrumentality regularly

and into the step-like formation shown in Fig. 6 and in the patent to myself, which I have referred to.

I am aware that certain expanded metal structures have been formed by simply simultaneously slitting and partially expanding the sheet-metal structure; but so far as I am aware the slotted blank, in which the slats or strips are merely twisted or inclined, is a new article of manufacture.

I claim, and desire to secure by Letters Patent, the following characteristic features:

1. As a new article of manufacture, a slotted blank for expanded metal structures, in which blank there are ribs alternating with slotted sections adapted to form a ribbed and slatted structure, the slats or narrow strips being slightly twisted or inclined in the said blank and the twists or inclinations of the slats in two adjacent sections being all in the same direction as measured along a section

or plane at right angles to the ribs, substantially as set forth.

2. As a new article of manufacture, a slotted blank for expanded metal structures, in which blank there are ribs alternating with slotted sections adapted to form a ribbed and slatted structure, the slats or narrow strips of two adjacent sections being oblique to the said ribs in opposite directions and being slightly twisted or inclined in the said blank, the said twists or inclinations being all in the same direction as measured along a section or plane at right angles to the ribs, substantially as set forth.

35

Signed this 3d day of July, 1900, at Niles, Ohio.

HERBERT E. WHITE.
